CLAIM

The ornamental design for a “paint colorant dispenser”, as shown and described.

DESCRIPTION

FIG. 1 is a left front perspective view of a paint colorant dispenser of this invention.

FIG. 2 is a front plan view of the paint colorant dispenser of FIG. 1.

FIG. 3 is a left side view of the paint colorant dispenser of FIG. 1.

FIG. 4 is a right side view of the paint colorant dispenser of FIG. 1.

FIG. 5 is a top plan view of the paint colorant dispenser of FIG. 1.

FIG. 6 is a right front perspective view of another paint colorant dispenser of this invention.

FIG. 7 is a top plan view of the paint colorant dispenser of FIG. 6.

FIG. 8 is a front elevational view of the paint colorant dispenser of FIG. 6.

FIG. 9 is a left side view of the paint colorant dispenser of FIG. 6; and,

FIG. 10 is a right side view of the paint colorant dispenser of FIG. 6.
